(57) **CLAIM**

The ornamental design for a butterflying hot dog slicer, as shown and described.

DESCRIPTION

FIG. 1 is a perspective view of one side and the front of the butterflying hot dog slicer according to my new design; FIG. 2 is a front elevation view thereof; FIG. 3 is a back elevation view thereof; FIG. 4 is a left side elevation view thereof; FIG. 5 is a right side elevation view thereof; FIG. 6 is a top plan view thereof; and, FIG. 7 is a bottom plan view thereof.

The dashed lines shown in the drawings illustrate environmental structure and form no part of the claimed design.
